UNITED STATES PATENT OFFICE.

MARK ANTHONY, OF STREATOR, ILLINOIS.

BED-SPRING.

1,185,575.

Specification of Letters Patent. Patented May 30, 1916.

Application filed April 29, 1915. Serial No. 24,769.

To all whom it may concern:

Be it known that I, MARK ANTHONY, a citizen of the United States, residing at Streator, in the county of La Salle and State of Illinois, have invented a new and useful Bed-Spring, of which the following is a specification.

The device forming the subject matter of this application is a spring bed.

It is a matter of common knowledge that 10 spring beds ordinarily become depressed along their longitudinal centers, and generally at their geometrical centers. As a consequence of the foregoing, a spring bed after a brief period of use becomes inoperative, or at least unsatisfactory in operation.

The present invention contemplates the provision of a spring bed embodying a plurality of sections of any desired number, the sections preferably being of rectangular 20 outline, and so constructed that one set of corners after another of the respective sections of the bed may be placed together adjacent the geometrical center of the bed, thereby doing away successively with de- 25 pressions at the center of the bed.

Another object of the invention is to provide novel means for uniting the respective sections of the bed with each other.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed, without departing from the spirit of the invention.

In the accompanying drawing:—Figure 1 40 shows the invention in top plan; Fig. 2 is a side elevation; Fig. 3 is a detailed perspective showing the means whereby the constituent sections of the bed are united.

Any of the well known forms of spring 45 bed sections may be employed in making up the present invention and the following description, so far as it deals with details may be taken as typical merely.

In the present invention, and in order to 50 present a concrete embodiment, four sections are shown, the sections being denoted respectively by the numerals 1, 2, 3 and 4, although more than four sections may be used if desired. Although the sections may 55 be variously constructed, each section is

shown as comprising an upper frame 5, a lower frame 6, cross members 7 connecting opposed portions of the lower frame 6, and cross members 8 connecting opposed portions of the upper frame 5, the cross members of the respective frames being rectangularly disposed as is common and well known in the art. Springs 9 may be assembled with the cross members of the respective frames. 60 65

The corners of the several sections 1, 2, 3 and 4 are denoted by the numerals 11, 12, 14, 15, 16, 17, 18, 19, 20, 21, 22, 23, 24, 25 and 26. As shown in Fig. 1, the corners 11, 10, 14 and 12 of the sections are shown as 70 being disposed adjacent each other, at the geometrical center of the bed. When the bed becomes depressed at its center, the sections 1, 2, 3 and 4 may be shifted with respect to each other to bring other corners 75 into close relation at the center of the bed. Thus, the corners 20, 26, 23 and 24 may constitute one group, the corners 18, 15, 16 and 17 may constitute another group, and the corners 22, 25, 21 and 19 may constitute still 80 another group. In this manner, the bed may be maintained in good condition adjacent its longitudinal center, much longer than would be the case with a common spring bed construction. 85

Any suitable means may be provided for connecting the several sections. In the present instance, the connecting means embodies a rod 27 provided at its ends with rectangularly disposed hooks 28. Intermediate its 90 ends, the rod 27 is folded upon itself to form a hook 29 extended in an opposite direction to the hooks 28. The hooks 28 are engaged around a portion of the top frame 5 of one section, and the hook 29 is engaged around 95 the corresponding part of the top frame of an adjoining section, as will be understood clearly from Fig. 1 of the drawings. Further, referring to Fig. 1, it is to be noted that the members 8 of the top frame 5 engage the hooks 28 on the ends of the rod 27 and hold the same in position against endwise movement. 100

Connecting means other than that shown in Fig. 3 may be resorted to, but the structure shown in Fig. 3 will be found of peculiar utility. 105

Having thus described the invention, what is claimed is:—

1. The combination with a pair of spring 110 bed sections embodying frames, of a rod extended longitudinally of the frames, the rod

being provided at its ends with transverse hooks and being provided with an intermediate hook, the intermediate and end hooks projecting in opposite directions and being engaged, respectively, with the frames.

2. The combination with a pair of spring bed sections, embodying frames, of a rod extended longitudinally of the frames, the rod being provided at its ends with transverse hooks and being bent upon itself intermediate its ends to form a loop, the loop be-

ing fashioned into an intermediate hook, the intermediate and end hooks extending in opposite directions and being engaged, respectively, with the frames.

15

In testimony that I claim the foregoing as my own, I have hereto affixed my signature in the presence of two witnesses.

MARK ANTHONY.
